UNITED STATES PATENT OFFICE.

CHRISTOPHER C. HARRIS, OF BOWLING GREEN, KENTUCKY.

TOBACCO-PRESS.

1,093,181.

Specification of Letters Patent. Patented Apr. 14, 1914.

Application filed May 23, 1913. Serial No. 769,527.

To all whom it may concern:

Be it known that I, CHRISTOPHER C. HARRIS, a citizen of the United States, residing at Bowling Green, in the county of Warren and State of Kentucky, have invented a new and useful Tobacco-Press, of which the following is a specification.

The present invention appertains to a tobacco press, and aims to provide a novel and improved apparatus of that character.

It is the object of the present invention to provide a simple, substantial and inexpensive device for compressing or prizing tobacco in a hogshead or other container.

Another object of the present invention is to provide a novel and improved attachment for a hogshead or container for preventing the compressed or prized tobacco from expanding or sponging back before the tobacco has been set, the attachment being removable in order to permit an additional supply of tobacco to be inserted into the hogshead to be compressed or prized.

With the foregoing and other objects in view, which will be apparent as the description proceeds, the present invention resides in the combination and arrangement of parts and in the details of construction herein-after described and claimed, it being understood that changes in the precise embodiment of the invention herein disclosed can be made within the scope of what is claimed without departing from the spirit of the invention.

The invention has been illustrated in its preferred embodiment in the accompanying drawing, wherein: Figure 1 is a side elevation of the apparatus, parts being shown in section. Fig. 2 is a sectional view taken on the line 2—2 of Fig. 1. Fig. 3 is a fragmental elevation. Fig. 4 is a fragmental perspective of a hogshead illustrating the attachment applied thereto.

In carrying out the invention, reference being had in detail to the drawing, there is provided a suitable base 1 having the uprights or standards 2 mounted thereon and carrying a beam 3 at their upper ends to provide a yoke or arbor. Disposed on the base 1 underneath the beams 3 is a scale platform 4 which is operatively connected to the scale arm 5 in any convenient manner, the scale arm 5 being preferably mounted upon one of the standards 2. It is to be understood that any suitable scale may be

employed, the same not forming a part of the present invention, and being provided primarily for permitting the tobacco to be weighed, either before or after prizing. An upright screw 6 is threaded through a nut 60 secured within the beam 3, and is provided at its lower end with a shoe 8. A crown wheel or gear wheel 9 is feathered upon the screw 6, and a thrust plate 10 is secured to the bottom of the beam 3 around the screw 6, the thrust plate 10 and the crown wheel 9 having complementary annular ball races in which are disposed the ball or antifrictional bearings 11. The plate 10 is designed to take the upward thrust of 70 the crown wheel 9, the ball bearings 11 reducing friction to a minimum.

In order to actuate or rotate the crown wheel 9, a shaft 12 is journaled through the respective standard 2 slightly below the upper end of the beam 3, and a pinion or spur gear 13 is keyed upon the inner end of the shaft 12 and intermeshes with the crown or gear wheel 9, a pendent or hanger 14 being attached to the beam 3 for supporting the inner end of the shaft 12. A roller 15 is also preferably hung from the beam 3 to contact with the upper face of the crown wheel 9 adjoining its periphery directly above the pinion 13 for maintaining the crown wheel and pinion in mesh.

An actuating shaft 16 has one end journaled to the respective standard 2 and has its other end journaled through an upright or pedestal 17 carried by the base 1, a crank 18 being secured to the last mentioned or outer end of the shaft 16 for manually rotating the same, although it is to be understood that the shaft 16 may be actuated by any suitable prime mover. A relatively small spur gear 19 is keyed upon the shaft 16 between the pedestal 17 and the respective standard 2, and intermeshes with a relatively large spur gear 20 keyed upon a counter shaft 21 journaled at its ends to the respective standard 2 and a second pedestal 17'. The counter shaft 21 has a sprocket wheel 22 keyed thereon, a chain 23 being trained over sprocket wheel 22 and the relatively large sprocket wheel 24 keyed upon the outer end of the shaft 12. It will thus be evident that the rotation of the actuating shaft 16 will impart a relatively slow and powerful rotation to the shaft 12 for rotating the crown wheel 9, the rotation of the

crown wheel serving to move the screw 6 upwardly or downwardly according to the rotation of the actuating shaft.

A suitable track 25 has its terminals extending to the platform 4 of the scales, it being understood that this track may be extended to any suitable point or points. A suitable truck 26 is adapted to travel on the track 25 to and from the scale or platform 4, it being designed that the truck 26 shall pass over the platform 4, if so desired. The truck 26 is designed to carry a hogshead or other container 27 to and from the scale platform. For purpose of compressing the tobacco in the hogshead 27, a follower or false head 28 is disposed within the hogshead over the tobacco. The attachment for the hogshead embodies a cross bar or member 29 adapted to rest on the upper end of the hogshead and having the cords or flexible elements 30 attached to its ends and carrying the hooks 31 at their free ends adapted to engage over the lower end or chine of the hogshead to maintain the cross bar 29 in position. The cross bar 29 is provided with the longitudinal slots 32 intermediate its central portion and ends through which the ratchet bars 33 pass, the lower ends of the ratchet bars 33 being pivoted to a block or shoe 34.

In use, it will be manifest that the hogshead may be readily placed on the platform 4, and after the hogshead has been filled with tobacco, the screw may be forced downward by rotating the crank 18, it being understood that the follower or false head 28 is placed over the tobacco, so that the shoe 8 of the screw will engage the follower or false head 28 to force the same downwardly into the hogshead and to thereby compress or prize the tobacco. It will be observed that the crown wheel 9 may be rotated readily, and with little effort, so as to effectively compress or prize the tobacco. The attachment as illustrated in Fig. 4 is preferably, although not necessarily, applied to the hogshead prior to the prizing of the tobacco, in order that when the follower or hogshead 28 is depressed, the ratchet bars 33 will slide 50 through and snap under the remote ends of

the slots 32 to lock the follower 28 against rising which might otherwise result due to the sponging or expansion of the tobacco. The shoe or foot 8 of the screw 6 is adapted to pass through an offset provided in the intermediate portion of the cross bar 9, and may contact with the block 34 if desired, it being observed that the ratchet bars 33 diverge upwardly so as to properly engage over the outer ends of the slots 32 when the block 34 is forced downwardly. In this manner, the tobacco is held under compression until the tobacco has set, in which event, the ratchet bars may be released by swinging them together or against the inner ends of the slots 32, which will permit the block 34 and follower 28 to be removed with the cross bar 29. A new supply of tobacco may then be inserted into the hogshead or container for a second operation, it being understood that the screw 6 has been previously raised or retracted from the hogshead. After several operations, the hogshead may finally become filled with prized tobacco, so that the permanent head may be applied to the hogshead, permitting the hogshead to be shipped or transported.

Having thus described the invention, what is claimed as new is:

In an apparatus of the character described, a cross bar adapted to be secured upon a container, said bar having its central portion offset for the passage of a compression member and having longitudinal slots intermediate said central portion and its ends, ratchet bars passing through the said slots, and a shoe to which the lower ends of the ratchet bars are pivoted, the shoe being designed for the engagement of the said compression member, and the ratchet bars diverging upward so as to engage over the remote ends of the said slots.

In testimony that I claim the foregoing as my own, I have hereto affixed my signature in the presence of two witnesses.

CHRISTOPHER C. HARRIS.
